LADY'S HANDBAG

Irving Wishnia, New York, N. Y.

Application July 14, 1950, Serial No. 173,742

2 Claims. (Cl. 150—28)

1

The present invention is directed to ladies' handbags, more particularly to a structure thereof which enables a plurality of decorative effects to be obtained with a single handbag.

In ladies' handbags as previously constructed there was usually provided a pair of side members suitably secured together as by hinges with a latch arrangement at the top for maintaining the bag in closed position. There was also provided a handle secured to the top of the handbag or straps of relatively great length adapted to be held on the shoulder of the user. Such handbags have certain decorative effects thereon so as to create individual styles. It has become customary for the user to wear a handbag having a design which matches the ensemble worn by the user. For this a separate handbag has been necessary so that in order to have a complete wardrobe, a relatively large number of bags was needed and the expense thereof was quite great.

The present invention is intended and adapted to overcome the disadvantages inherent in prior structures of the type described, it being among the objects of the present invention to provide a lady's handbag having certain portions thereof detachable and allowing the replacement thereof with similar members of different design.

It is also among the objects of the present invention to provide a lady's handbag with a removable side panel and/or a removable strap or handle which may be quickly and conveniently replaced by similar elements.

It is further among the objects of the present invention to provide a mechanical structure associated with the side of the handbag whereby a panel may be inserted within a frame and held in position flush with the face of the frame.

In practicing the present invention, there is provided a handbag of a construction in which there is a pair of side members in the form of frames having relatively large openings. At least one of these frames, and preferably both, is provided with a panel of a size and shape corresponding to the size and the shape of the opening in the frame. The inside of the frame is provided with a plate of relatively stiff material which acts as a closure for the side of the handbag. A bolt or the like passes through the plate and extends outwardly. The panel has a hole corresponding in position and size with the bolt so that the panel may be slipped over the bolt and nested within the frame. A nut or other element threaded on the end of the bolt holds the panel detachably in position.

There is also provided usually on the ends of

5 one or both of the frames clip members which are fixed to said frames. These clips have hook members adapted to retain an eye so that it is held detachably therein. A strap or handle is secured to a pair of such loops. By this construction the panel and the strap or handle may be made of similar material and of the same design. With each handbag there is provided a plurality of such pairs of elements. The user, desiring to have a bag of certain design to fit a specific ensemble, removes the panel by unthreading the nut, removes the strap by withdrawing the loops from the hooks and replaces them with similar elements of different design.

10 In the accompanying drawing constituting a part hereof, in which like reference characters indicate like parts,

15 Fig. 1 is a perspective view of a lady's handbag made in accordance with the present invention, some parts being shown broken away for clearness;

20 Fig. 2 is a fragmentary, vertical, cross-sectional view of one of the side members of the handbag taken along line 2—2 of Fig. 1; and

25 Fig. 3 is a perspective view of a panel adapted to be fitted into the side of the frame.

The handbag consists essentially of a relatively stiff frame, rectangular in shape and having sides and ends 1, 2, 3 and 4. A duplicate frame for the other half of the handbag has sides and ends 7, 8, 9 and 10 corresponding to similar elements on the first-named frame. Each of the frames is recessed as shown at 5 to form a space which will receive a panel. Plate 6 of relatively stiff material, which may be cardboard, wood or synthetic materials, is inserted on the side of the frame adjacent opening 5 and is secured in position as by cementing. It thus forms a closure for the side of the handbag. The meeting edges 11, 12 and 13 complete the enclosure of the handbag. Hinges are provided at lower meeting edges 13 and a pair of latch members 14 and 15 at the top of the handbag are secured one to each of the frames.

30 35 40 45 50 55 60 65 70 75 80 85 90 95 The panel 16 is rectangular and is secured to a base 17 of the same shape made of a relatively stiff material which may be similar in character to that of plate 6. The face of panel 16 may have any desired decorative effects and may, for example, be of fabric with a relatively soft padding at the undersurface thereof. The panel may be secured to the base by cementing or other means. A hole 18 substantially centrally located is formed in both the panel and the base, the latter having a flange 19 at said opening. A grommet

20 is anchored in the opening and serves to hold the panel and base as a unit.

Bolt 21 passes through grommet 20 with the head of the bolt on the inside of plate 6 and the shank thereof extending beyond the plane of the side face of the frame. Lining 22 within the frame serves to conceal plate 6 and bolt 21. Panel 16 is inserted over bolt 21 with the plane of the face 23 thereof in alignment with the face 24 of the frame. A thumb nut 25 is threaded on 10 the end of the bolt, the diameter of the nut being sufficiently great to contact a substantial area of the face 23 of the panel.

On the ends of one or both of the frames is provided a clip 26 having hook 27 at the upper 15 end thereof and fixed to the frame as by rivets, 28. Loop 29 has strap 30 threaded through it, the end 31 of said strap being stitched at 31 to form a holding means for said loop. The other end of the strap is similarly constructed.

If the user is wearing an ensemble which has a predominantly blue motive and desires a handbag to match, the wearer will use a panel 16 having a corresponding color and design and will use a strap which is of the same or similar 25 design. If the user now is wearing an ensemble having, say, a pink motif, then the handbag may be adapted for such wear by removing nut 25, removing panel 16 and replacing it with a suitable panel having a pink motif. The wearer will also unsnap loops 29 from the clips and insert a strap having the correct motif or design. Thus the wearer for slightly more than the cost of a handbag will have at her disposal a substantial 35 number of handbags to fit a number of occasions. Thereby for a modest cost a complete handbag wardrobe is obtainable.

The essence of the invention is the provision of removable and replaceable covers and handles. In addition, a single frame is provided into which the removable elements fit so as to appear as a finished article with the several elements being integral with the bag. At the same time they may be readily detached and replaced.

Although the invention has been described 45 setting forth a single specific embodiment thereof, various changes in the details of construction may be made within the spirit of the invention. For instance, strap 30 may be attached on the top of the handbag rather than on the ends thereof. Clips 26 may be of different form and character. The shape of opening 5 as well as the shape of the frame may be of any suitable character. In such case the panels will be suitably shaped. Bolt 21 and hole 18 may be differently positioned than shown and the bolt and nut arrangement may be reversed. Base 17 of the panel may in some cases be omitted as well as plate 6.

While, as shown, the handbag is provided with but a single bolt and nut to hold each panel, a plurality of such elements may be used for their decorative and functional effects, and they may be embellished so as to conceal their functional character. The frame may be of wood, metal, shell, plastic or other materials suitable for the purpose, and it may be made in various colors and designs.

These and other changes may be made in the details of the invention within the principles herein set forth and the invention is, therefore, to be broadly construed and not to be limited except by the character of the claims appended hereto.

I claim:

1. A lady's handbag with detachable panels comprising a pair of side members hinged together at the lower ends thereof, latch elements at the top of said members cooperating to close said handbag, a rigid frame having a relatively large central opening for at least one of said side members, a relatively stiff plate on the inner face of said side member, an outwardly extending bolt anchored in said plate, a separate panel of a size and shape corresponding with said opening having a hole in said panel adapted to receive said bolt, the outer face of said panel being flush with the outer face of said frame, a relatively stiff base on which said panel is mounted, a lining on the inner face of said side member and covering said bolt, a grommet in said hole and fixed to said base and panel, said bolt passing through said grommet, and a nut for said bolt adapted to fit over the outer face of said panel.

2. A lady's handbag with detachable panels comprising a pair of side members hinged together at the lower ends thereof, latch elements at the top of said members cooperating to close said handbag, a rigid frame having a relatively large central opening for at least one of said side members, a relatively stiff plate on the inner face of said side member, an outwardly extending bolt anchored in said plate, a separate panel of a size and shape corresponding with said opening having a hole in said panel adapted to receive said bolt, the outer face of said panel being flush with the outer face of said frame, a relatively stiff base on which said panel is mounted, a lining on the inner face of said side member and covering said bolt, a grommet in said hole and fixed to said base and panel, said bolt passing through said grommet, said bolt passing through the central portion of said panel, and a nut for said bolt adapted to fit over the outer face of said panel.

IRVING WISHNIA.
